UNITED STATES PATENT OFFICE.

JAMES A. PATTERSON, OF SHERMAN TOWNSHIP, CLAY COUNTY, KANSAS.

ROTARY ROAD-MAKING MACHINE.

1,253,876.

Specification of Letters Patent. Patented Jan. 15, 1918.

Application filed July 3, 1915. Serial No. 37,941.

To all whom it may concern:

Be it remembered that I, JAMES A. PATTERSON, a citizen of the United States, residing in the township of Sherman, in the county of Clay and State of Kansas, have invented certain new and useful Improvements in Rotary Road-Making Machines, of which the following is a specification, reference being had to the accompanying drawings, which form a part hereof.

My invention relates to improvements in road-making machines in which a rotating shaft is provided with means for gathering and distributing the earth to the proper grade for the roadbed, and the objects of my improvements are: first, to provide a road-making machine which, while excavating the ditches at the sides of the road, will also loosen, pulverize and distribute the earth at a proper gradient upon the roadbed; second, to provide a road-making machine comprising grade shovels secured to a revolving shaft operated by means forming a part of the machine or the operative portion thereof constructed as an attachment to a traction engine or other motive power; third, to afford facilities for the proper adjustment of the wings independently of each other for the purpose of regulating the depth so the shovels shall penetrate the soil; fourth, to provide a road-making machine in which the shovels attached to rotating shafts gradiently move the earth toward the middle or to the opposite side of the roadbed, thus forming the desired contour thereof; fifth, to provide a road-making machine in which the wings may be operated separately or in conjunction and thus grade one side of the roadbed alone or both sides together and completing the road in one passage; sixth, to provide a road-making machine which will reduce the unevenness of the roadbed by cutting down the raised portions and moving sufficient soil ahead to fill the depressions, thus evening the surface to the desired contour in one passage of the machine over the roadbed.

I attain these objects by means of the mechanism hereinafter described and illustrated in the accompanying drawings, in which,—

Figure 1 is a plan view of my improved road machine;

Figs. 2 and 3 are detailed views on an enlarged scale of the shovels or diggers employed;

Fig. 4 is a longitudinal vertical section

on an enlarged scale through the center of the machine, showing the driving mechanism;

Fig. 5 is a side elevation of the complete machine shown in Fig. 1;

Fig. 6 is a detailed side elevation of the frame for supporting the controlling cables;

Fig. 7 is a sectional elevation on an enlarged scale of one of the winding drums, with its associated pawl and ratchet;

Fig. 8 is a detailed section showing one of the improved universal joints which I employ;

Fig. 9 is a transverse section on the line 8—8 of Fig. 8, looking in the direction of the arrow;

Fig. 10 is a fragmentary plan view showing part of the driving mechanism;

Fig. 11 is a view similar to Fig. 8, showing one of the universal joints with the parts reversely arranged; and,

Fig. 12 is a view similar to Fig. 3, showing a modified construction of shovel.

Referring to the drawings in detail, my improved machine comprises a frame formed of longitudinal, spaced center sills 1, and side sills 2, connected at the rear by an end sill 3. At the front, the side sills converge toward each other and are united by a plate 4. The machine is supported on main ground wheels 5, mounted near the rear of the machine on an axle 6, and preferably having wide treads, as shown. At the front of the machine is a pair of small guide wheels 7, mounted on an axle 9, pivoted at its center to a king bolt 12, passing through the plate 4. A toothed segment 11 is secured to the axle 9 and meshes with a pinion carried at the lower end of a steering shaft 10, having the usual hand wheel. Other suitable steering mechanism may, if desired, be employed, as that shown forms no part of the present invention.

The machine as shown is designed to be drawn by a traction engine or other suitable power, and in order to operate the shovels hereinafter described, rims 32 are secured to the ground wheels 5 and are engaged by sprocket chains 31, which take over sprocket wheels 30, secured to stub shafts 67. These shafts are journaled in the side sills 2 and carry at their inner ends pinions 74. The pinions 74 are arranged to mesh with other pinions 55, which are rigidly secured to a shaft 28, extending transversely across the frame of the machine.

Rigidly mounted upon the center of the

shaft 28, between the center sills 1, is a wheel 29, having on its opposite sides clutch faces adapted to engage with corresponding clutch faces carried by a pair of sprocket wheels 26 and 27, loosely mounted on the shaft 28, as clearly shown in Fig. 10. The sprocket wheels 26 and 27 are capable of longitudinal movement on the shaft 28 so that the clutch members carried thereby 10 can be shifted into and out of engagement with the corresponding clutch members carried by the wheel 29, whereby the motion of shaft 28 can be transmitted to either or both of the wheels 26 and 27, as desired. These 15 wheels may be shifted by means of levers 53 and 54, connected with suitable operating mechanism (not shown).

The improved excavating or earth-moving device which I have designed consists of two sets or series of revolving shovels, as will now be described. By reference to Figs. 2 and 3, it will be seen that each of these shovels comprises a shank 56, secured to a hub 62, and preferably having a brace member 57 for strengthening the same. To the ends of the shank 56 are secured the curved shovel members 58. As shown in Figs. 2 and 3, the shovels 58 are secured to the shanks 56 by means of bolts 61, working 25 through slots 60 in the shank 56, the shovels preferably having folded-over portions 59, adapted to embrace the edges of the shank 56, so as to rigidly maintain the parts in position. By means of the sliding bolt and 30 slot connection just described, it will be obvious that the shovels can be positioned at different distances from the hub 62, as desired.

The shovels just described are mounted 40 upon a pair of shafts 15, extending from each side of the machine, as clearly shown in Fig. 1. These shafts are preferably square and the hubs 62 are provided with square openings 63, arranged to fit over such 45 shafts. A series of shovels is secured to each shaft 15, the shovels being spaced apart a suitable distance and the blades turned at such an angle that the earth is thrown inwardly toward the center of the 50 machine. The shovels are set at progressively varying angles on the shaft so that the blades are arranged in a spiral series therearound. By adjusting the blades 58 on the shanks 56, as described, the series of 55 shovels may be made to present any desired contour so as to give to the road any shape or profile which may be necessary. As shown, the end shovels are adjusted so as to be considerably longer than those nearer the 60 center, and by this means a drain or gutter is formed at each side of the roadbed.

Each shaft 15 is connected at its inner end to the outer ends of a central transverse shaft 19, suitably journaled in the frame 1. 65 This connection is by means of a universal

joint 17, the details of which are shown in Fig. 8. Referring to this figure, it will be seen that the shaft 15 carries an enlargement 51 on its end, which enlargement is received within a socket or casing 47. The casing is 70 formed of two members having flanges 71 secured together by means of bolts 52. The enlargement 51 is provided with a plurality of rounded radial teeth or projections 72, and the outside member of the casing 47 75 is formed with a similar series of pockets 46. The casing is further provided with a central aperture through which the shaft 15 extends, and around the inside of this aperture is formed an annular groove or channel 73, in which works a similarly shaped rib formed on the enlargement 51. The opening in the casing 47 is preferably flaring and somewhat larger than the shaft 15, and is closed by means of a plate 48, surrounding the shaft 15 and held against the casing 47 by means of a spring 50, the other end of which bears against a collar 49.

By virtue of the construction just described, it will be apparent that the shaft 90 15 is free to assume different angular positions with respect to the shaft 19. It will also be noted that the shovels 58 are set so that an outward thrust is developed when the machine is operating, such outward 95 thrust tending to cause the projection 72 to seat firmly in the pockets 46 and thus establish a driving connection between the shafts 19 and 15. In other words, such driving connection is established when the shovels 100 enter the earth and is maintained by the thrust of the earth against such shovels.

Rigidly secured to the shaft 19, intermediate its ends, is a sprocket wheel 21, and a sprocket chain 24 meshes with this wheel 105 and with wheel 26, journaled on the shaft 28. When wheel 26 is clutched to wheel 29, as above described, it is evident that the shaft 19 will be driven and the shovels caused to operate.

At the rear of the shafts 15 and their associated shovels, I provide a second pair of shafts 16, arranged substantially parallel to the shafts 15, but much shorter than such shafts. The shafts 16 are provided with a 115 series of shovels in all respects similar to those described in connection with the shafts 15, except that they are reversely arranged. That is to say, while the shovels of shafts 15 are so shaped as to throw the earth inwardly toward the center of the machine, the shovels of shaft 16 are so set as to throw the dirt outwardly from the center of the machine. Each of the shafts 16 is connected at its inner end with the outer end of a second transverse shaft 20, journaled in the frame 1, parallel with the shaft 19. These connections are by means of universal joints 18, identical with those described in connection with shafts 15 except that they are re- 130

versed, as shown in Fig. 11. In this figure, corresponding parts are designated by the same reference numerals as in Fig. 8. In operation, the two parts of the joints are forced into coöperative relation by means of the inward thrust generated by the engagement of the shovels with the earth.

Secured to the shaft 20, intermediate its ends, is a sprocket wheel 22, around which 10 passes a sprocket chain 25, engaging the sprocket wheel 27, journaled on the shaft 28. When the sprocket wheel 27 is clutched to the wheel 29, as above described, it is obvious that the shaft 20 and the associated 15 shafts 16 will be rotated.

In order to guide the material to one side or the other of the roadbed, as required, I provide a scraper 68, mounted on a vertical shaft 30 and having an operating lever 65, 20 secured thereto, such lever engaging a notched rack 66, whereby it is held in any desired adjusted position.

The driving mechanism, including the sprocket wheels 26, 27, 21, and 22, and their 25 associated parts, are inclosed within a housing 23, as shown.

The outer ends of the shafts 15 and 16 are supported by means of suitable braces 13 and 14, pivoted to the ends of the axle 6. 30 In order to raise and lower the shafts 15 and 16 and their associated shovels, I provide controlling cables 38 and 39. These cables pass around guide pulleys 34, 35, 36, and 37, carried by laterally extending arms 33, secured to the frame members 1 and 2, and are attached at their free ends to the braces 13 and 14. At their other ends, these cables are wound upon drums 40, which 35 drums are provided with operating handles, 40 42, and pawl and ratchet mechanism 43-44, by means of which the tension in the cables is maintained. The drums 40 are journaled in suitable standards 41, carried by the frame 2.

45 Instead of forming the shovels 58 in pairs, as shown in Figs. 2 and 3, I may construct them as illustrated in Fig. 12, in which but a single shovel is employed, such shovel being carried by an arm 79, secured 50 to the hub 62.

While I have described my road machine as adapted to be drawn by a traction engine and the shovels driven through the ground wheels 5, I also contemplate propelling the machine under its own power. 55 This can be readily accomplished by mounting upon the machine a suitable engine (not shown) and operatively connecting the drive shaft of such engine with the wheel 29. To this end, the wheel 29 would be 60 formed with gear teeth, as shown in the drawings, so as to mesh with a gear wheel driven by the engine. With this arrange-

ment, the machine would be propelled by means of the chains 31, driving the ground 65 wheels 5, as will be readily understood.

In operation, as the machine moves along, the first or main series of shovels dig up the earth and work it toward the center of the roadway, excavating the side drains or 70 gutters at the same time, and filling in all hollows or depressions. The second or auxiliary series of shovels serve to level down the ridge of earth thrown up in the center by the main shovels, and to flatten the crown 75 of the road, so as to fit it for travel. It will thus be seen that a complete and finished road surface, including gutters, is formed by a single passage of my improved machine over the roadway. 80

What I claim is:—

1. In a road grader, a supporting frame, wheels on which said frame is mounted, a shaft extending transversely of said frame, a series of spirally arranged radial arms 85 mounted on said shaft, said arms being of progressively increasing length from one end of the shaft to the other, shovels carried by said arms and set to move the earth transversely of said frame, means for driving said shaft, and means by which said shovels may be individually adjusted radially of said arms, whereby the profile of said series of shovels may be varied as desired. 90

2. In a road grader, a supporting frame, wheels on which said frame is mounted, a central shaft journaled in said frame and extending transversely thereof, and a pair of outer shafts extending one on each side 100 of said frame, shovels secured to said outer shafts, means for raising and lowering the outer ends of such shafts so as to bring said shovels into and out of contact with the earth, means for driving said central shaft, 105 and means between said central shaft and outer shafts for establishing a driving connection from the former to the latter only when the shovels are moved into engagement with the earth. 110

3. In a road grading machine, a supporting frame, wheels on which said frame is mounted, two transverse series of rotary shovels carried by said frame, and means for driving said shovels, the two series of shovels being arranged one behind the other in overlapping relation, the shovels of one series being shaped to throw the material toward the center of the machine, and the shovels of the other series tending to throw 115 the material away from the center. 120
